UNITED STATES PATENT OFFICE.

IRWIN M. KROHN AND MICHAEL J. SULLIVAN, OF CINCINNATI, OHIO.

PROCESS OF COVERING HEELS.

1,190,775.

Specification of Letters Patent. Patented July 11, 1916.

Application filed February 7, 1916. Serial No. 76,547.

To all whom it may concern:

Be it known that we, IRWIN M. KROHN and MICHAEL J. SULLIVAN, citizens of the United States, and residing at Cincinnati, in the county of Hamilton and State of Ohio, have invented a new and useful Improvement in Processes of Covering Heels, of which the following specification is a full disclosure.

10 Our invention relates to a new and improved method of covering the heel of a shoe, and to the resultant new and improved product.

15 The primary object of the invention is to cover the heel after it is attached to the shoe, or in conjunction with the heel attachment to the shoe.

20 The invention has particular use in relation to the ordinary leather heel, built on and attached to the shoe in the usual way. But the invention may also be used in connection with a one-piece heel, and the covering process herein disclosed enables either a one-piece heel or a sectionally assembled 25 heel to be secured to the heel seat while the parts are in position on the last, so that the heel covering is not an independent operation, but coördinated with conventional heel- 30 ing processes and machines.

35 The particular advantage of the process as regards a lift heel is that a heel can be sectionally built upon a lasted shoe and nailed from the outside to the heel seat in the ordinary manner by standard machines while the shoe is lasted, and the outer heel surface can be covered after the heel is completed and attached so that a lift heel can be covered, saving the burnishing operation, and requiring no unlasting and relasting 40 of the shoe parts, the heel cover having a margin preferably lasted directly to the non-exposed heel seat portion of the lasted shoe parts. In the preferred form the lift joints as well as the heel seat edge of the outsole will be concealed under said cover, and a margin of said cover is held firmly in the non-exposed heel seat portion of the lasted shoe parts.

45 It is well-known that leather or kid covered wooden heels have been in use. Such heels have not the advantages nor qualities of leather heels in wear or appearance. Moreover such covered wooden heels have to be bought from a special manufacturer and attached to the shoe by an inconvenient and expensive method. Therefore, prominent

advantages of the present invention are, that it enables the use of a covered leather heel; it enables the shoe manufacturer to make, attach, and cover heels in his own factory; it enables the heel-covering process to be economically and efficiently correlated with conventional processes and machines as used in forming and attaching leather heels to a lasted shoe upper; and it enables the making 65 of a shoe with a covered heel, the process being available in connection with the making of any type of shoes.

The features of the invention will be understood with reference to the accompanying drawings, forming a part of this specification, in which:—

Figure 1 is a side elevation of the conventional lasted upper before the outsole and heel are attached, and with the heel covering shown in its first position of attachment. Fig. 2 is a similar view, showing the outsole and heel applied, with the heel still uncovered. Fig. 3 is a similar view, showing the covered heel and the outsole operations completed.

The conventional shoe parts, upper, counter, lining and insole, being lasted as usual on the last 2, prior to the outsole operation, a heel cover 3 is placed around the heel of the last with a margin turned in over the lasted heel margin of the upper, and it is preferably secured thereto by nails 4, so as to be firmly lasted directly to the upper, the unattached portion of the heel cover extending upwardly and around the lasted heel portion of the upper so as to be entirely out of the way as regards the subsequent outsole operations. This cover is of suitable ornamental material constituting the veneer or trimming, and it is patterned to fit the given heel contour, that is, an outer or curved heel surface, as distinguished from the breast of the heel. After the heel cover margin is so secured to the lasted upper 90 heel margin, the outsole 8 is laid and secured to the shoe parts upon the bottom of the last, and the heel end of the outsole covering the attached margin of the heel cover forms the direct seat for the heel. The heel 95 is nailed from the outside to this outsole heel seat in the ordinary way and by standard machines, while the upper parts of the shoe are so lasted, and then the unattached portion of the heel cover 3 is drawn from its position around the heel of the last, as shown in Fig. 1, over the heel seat edge of 100

105

110

the outsole and over the outer or rough heel surface 7, and it is adhesively secured thereto so as to conceal the outsole heel seat edge and outer heel surface and lift joints, the 5 cover extending as it were contiguously from the heel portion of the upper. Preferably the forward edges of the heel cover are adhesively secured directly to the heel breast and covered by a flap 9 skived from 10 the heel end of the outsole. The product resulting from this method and disclosed herein constitutes an independent invention for which I have filed separate application. 15 The heel 5 may be a one-piece heel, either curved or straight, or it may be a lift heel, the first section of which is attached to the heel seat, and the next section attached to the first section. In short, the heel, the rear and side portions of which constitute the un- 20 finished surface 7, is attached to the heel seat in the ordinary manner, while the parts are lasted, and the loose portion of the cover is drawn off of the heel of the last and around the surface 7 and caused to conform 25 thereto, and is adhesively secured thereto, thus also serving to cover the heel seat portion of the outsole. The heel and shoe upper above the heel, thus present the appearance 30 of a continuous leather or kid surface, with only a single slight joint 12, indicating the heel seat line between the upper and heel. The bottom lift 11 is attached to the heel as usual. With a shoe finished by this method, the heel can be repaired by taking off or re- 35 placing the lifts in the usual manner, the shoe is more durable and presents a neater appearance. Therefore, the process in addition to the advantages from a manufacturing point of view, produces in every way a 40 new, better and higher grade product, and the process affords a cheaper and superior method of producing shoes with covered heels than is possible with the use of covered heels of such construction or material 45 as require extra hand work, and the manufacturer can make, cover and attach his heels without the necessity of varying his ordinary system, processes and machines. Again, it will be noted that in the preferred method 50 the heel cover is primarily attached to the heel seat portion of the upper and counter, and again attached to the heel itself, so as to increase, rather than weaken the forces holding the heel to the shoe. 55 Slight variations in the order of steps or exact method may be used, without departing from the principles of this invention or discovery, as, for instance, the heel surface 7 may be first covered, and then the upper 60 margin of the cover can be tucked into the heel seat and secured coincidently with the securing of the heel itself to the heel seat, or other slight changes can be made, the cover being attached both to the heel surface 65 and to the non-exposed heel seat portion of

the shoe coördinately with the operation of placing and securing the heel in place.

Having described our invention, we claim:

1. In the art of shoe making, the process 70 comprising the steps of lapping the margin of a heel seat cover over a heel seat surface of a lasted shoe and then securing it thereto.

2. In the art of shoe making the process 75 comprising the steps of securing the margin of a heel cover upon a heel seat portion of a lasted shoe upper, the unattached cover portion being folded around the heel portion of the lasted upper, laying and attach- 80 ing the outsole, attaching the heel upon the outsole heel seat, drawing the unattached portion of the heel cover from the lasted upper over an outer heel surface and securing it thereto. 85

3. In the art of shoe making the process comprising the steps of nailing the margin of a heel cover to the heel margin of a lasted upper, securing the outsole to the lasted upper parts, securing the heel to the heel seat, 90 and securing the unattached portion of the heel cover to the outer heel surface of the attached heel.

4. In the art of shoe making the process comprising the steps of nailing a heel cover 95 to a non-exposed heel seat portion of a lasted shoe, attaching the heel and securing the unattached cover portion to the outer heel surface.

5. In the art of shoe making, the process 100 comprising the steps of securing a margin of a heel cover to a non-exposed heel seat portion of a lasted shoe, securing an outsole over said cover margin, sectionally assembling and securing a laminated heel upon 105 the heel seat of the outsole and drawing the unattached cover portion around the outer heel surface and securing it thereto to conceal the lift joints and outsole heel seat edge. 110

6. In the art of shoe making, the process comprising the steps of attaching one portion of a heel cover to a non-exposed heel seat portion of a lasted shoe, attaching a heel to its heel seat and attaching the other 115 portion of said heel cover to the outer surface of the attached heel.

7. In the art of shoe making, the process comprising the step of lasting the margin of a heel cover upon the heel seat portion of a 120 shoe, the free portion of the cover being folded back out of the way of subsequent operations for attaching the outsole and heel.

8. In the art of shoe making, the process 125 comprising the step of lasting the inner margin of a heel cover upon the heel seat portion of a lasted upper, the free portion of said cover being folded back out of the way of subsequent operations for attaching the 130

outsole and heel, securing an outsole and heel in place, and then drawing the free portion of said cover from its folded position over an outer heel surface and securing it thereto.

9. In the art of shoe making, the steps in the process of covering an exposed heel surface with a cover consisting in lapping the margin of a heel cover around the heel seat 10 of a lasted upper and securing said margin

between non-exposed heel seat surfaces of the shoe.

In witness whereof, we hereunto subscribe our names, as attested by the two subscribing witnesses.

IRWIN M. KROHN.

MICHAEL J. SULLIVAN.
